(57) **CLAIM**

The ornamental design for a circular speakerphone, as
shown and described.

DESCRIPTION

FIG. 1 is a front-right-top perspective view of a circular
speakerphone;

FIG. 2 is a top view thereof;

FIG. 3 is a front view thereof;

FIG. 4 is a bottom view thereof;

FIG. 5 is a back view thereof;

FIG. 6 is a right view thereof; and

FIG. 7 is a left view thereof.

The broken line showing of environmental features in FIGS.
4, 5, and 6 is for illustrative purposes only and forms no part
of the claimed design.
